UNITED STATES PATENT OFFICE.

CARL W. VOLLMANN, OF MONTREAL, QUEBEC, CANADA.

COMPRESSOR.

Application filed April 28, 1921. Serial No. 465,349.

To all whom it may concern:

Be it known that I, CARL W. VOLLMANN, of the city of Montreal, Province of Quebec, Dominion of Canada, a subject of the King of Great Britain, have invented certain new and useful Improvements in Compressors; and I do hereby declare that the following is a full, clear, and exact description thereof.

This invention relates particularly to the 10 mechanical compression of air or any gaseous fluid and has for its object to produce a compressor which will have greater capacity for work and consequently higher efficiency than other compressors of the same size.

15 The invention has for its object to obtain from a comparatively small machine a relatively large capacity for compression.

To this end the invention, broadly stated, consists in employing rotary action and converting the same directly into reciprocatory action without separate intermediate mechanism and within the same cylinder, the function of this combination of elements being to take in air or other gaseous fluid and discharge the same under compression.

More specifically stated the invention consists of a unitary cylinder in which a reciprocatory piston is located and a rotary guiding member, each of these members having as an integral part one element of a duplex cam mechanism adapted to mutual operation, the rotary member being provided with a shaft by which rotation may be imparted thereto from any available source and the 30 reciprocating member exerting compressive force upon the air or other gaseous fluid automatically fed into the compression end of the cylinder.

For full comprehension, however, of my 40 invention reference must be had to the accompanying drawings in which similar reference characters indicate the same parts, and wherein:

Figure 1 is a longitudinal vertical sectional view of my compressor;

Figure 2 is a similar view with the operating port in a different operating position;

Figure 3 is a face view of the cam end of the rotary member;

Figure 4 is a similar view of the corresponding end of the piston;

Figure 5 is a sectional view taken on line 5-5 Fig. 1; and

Figure 6 is a horizontal sectional view taken on line 6-6 Figure 1, the operating shaft being shown in plan view.

The cylinder 1 of my improved compressor has intake port 2 and outlet port 3. The operating shaft is indicated at 4 and it has a rotary cylindrical member 5 which 60 may be separately formed and rigidly connected thereto or an integral part thereof. The piston is indicated at 6. The contiguous ends of the rotary member and piston are provided with circumferential cams 7 65 and 8 respectively and presented in one case by a projecting flange and in the other case by a set-back shoulder, these cam faces being disposed at corresponding angles in order that they may register and lie in contact 70 with each other in one operating position and mutually cause separation of these contiguous ends in a diametrical opposite operating position. The rotary member is chambered, as indicated, at 10 and has intake 75 ports 12 in constant open communication with a circumferential chamber 110 formed by a concavity in the surrounding wall of the cylinder, such chamber 110 communicating with intake port 2, otherwise the interior presents a closed chamber excepting for valve ports 14. The piston is also chambered as at 15 and has valve ports 16 and the interior of its lower side is formed with a guide-way 17 for a guiding tongue 18 80 cast on or otherwise carried by the cylinder head 19. A cylindrical spring 20 tends to maintain the piston with its cam face in contact with the cam face of the rotary member. 85

The rotary member and piston are provided with piston rings 21 and 22 respectively and the end of the cylinder through which the driving shaft 4 enters is provided with a stuffing box 25 and ball bearing 120 90 for absorbing the thrust due to the compressive force; while the interior of the cylinder wall is formed with lubricating grooves 26 into which lubricant may be introduced in any preferred manner, and by which the shaft, rotary member and piston are lubricated. 95

Operation.

The intake port 2 is connected to any 105 available air or gas supply and the outlet port 3 to the accumulator or other point of distribution or storage. The rotation of shaft 4 and with it the rotary member 5 causes the piston 6 to move axially towards the port 3 through the action of the engaging cam faces 7 and 8. During this move- 110

ment gas is intermittently drawn from the port 2 into the interior of the rotary member 5 and through valve ports 14 into the space between the adjacent ends of the rotary member and piston. Continuous rotation causes the release of the cam 8 by the cam 7, the protruding portion or rise of the latter registering with the depression of the cam 8 as shown in Figure 2, and permitting 10 the spring and back pressure of the gas in port 3 to return the piston, thereby compressing the gas, between the valvular ends of the rotary member and piston, until the accumulated pressure opens the valves 16. 15 The operation augments the compressed gas in the compression end of the cylinder. During each revolution of the rotary member the mutual operation of the cam faces projects the piston towards the port 3 and 20 as the spring 20 and the back pressure of the compressed gas keeps the piston in bearing relation with the cam of the rotary member and causes it to return to a position with the face of its valvular end in close 25 proximity to the valvular end of the rotary member. The compressor is designed as a high speed machine and the port 12 is designed to constantly admit gas.

It will be seen from the foregoing that 30 with my improved compressor a simple member developing rotary motion is caused without separate intermediate mechanism to convert this rotary motion into axial reciprocal motion and employ this latter motion 35 to compress air or other gaseous fluid.

What I claim is as follows:

1. A compressor for air and other gaseous fluid consisting of a cylinder having intake and outlet ports near its opposite ends, and 40 a cylinder head; such cylinder containing a chambered rotary member near one end and a chambered reciprocal compressive member near its opposite end, the chambered rotary member being adapted to receive air or other 45 gaseous fluid from the intake port, valve controlled ports in one end of the chambered rotary member, the adjacent end of the compressive member having valve controlled ports, means whereby the rotation of the 50 rotary member imparts axial reciprocal movement of the compressive member and means for preventing rotation of the reciprocal compressive member.

2. A compressor for air and other gaseous 55 fluid consisting of a cylinder having intake and outlet ports near its opposite ends, and a cylinder head, and containing a rotary member near one end and a chambered reciprocal compressive member near its opposite end, a port in the chambered rotary member adapted to, at times, register with the intake port, valve controlled ports in one 60 end of the chambered rotary member, the adjacent end of the compressive member having valve controlled ports, cam mecha-

nism whereby the rotation of the rotary member imparts axial reciprocal movement to the compressive member and means for preventing rotation of the reciprocal compressive member.

3. A compressor for air and other gaseous fluid consisting of a cylinder having intake and outlet ports near its opposite ends, and a cylinder head, and containing a rotary member near one end and a chambered reciprocal compressive member near its opposite end, a port in the chambered rotary member adapted to, at times, register with the intake port, valve controlled ports in one end of the chambered rotary member, the adjacent end of the compressive member having valve controlled ports, means whereby the rotation of the rotary member imparts axial reciprocal movement to the compressive member consisting of coacting cam faces upon the said respective adjacent ends of the rotary and compressive member and means for preventing rotation of the reciprocal compressive member.

4. A compressor for air and other gaseous fluid consisting of a cylinder having inlet and outlet ports near its opposite ends, and a cylinder head, and containing a rotary member near one end and a chambered reciprocal compressive member near its opposite end, a port in the chambered rotary member adapted to, at times, register with the intake port, valve controlled ports in one end of the chambered rotary member, the adjacent end of the compressive member having valve controlled ports, the rotary member having one end of reduced diameter and protruding towards the compressive member and surrounded by an annular cam face, and the adjacent end of the compressive member having an inset face and surrounding cam of annular form corresponding with the cam of the rotary member, means whereby the rotation of the rotary member imparts axial reciprocal movement to the compressive member and means for preventing rotation of the reciprocal compressive member.

5. A compressor for air and other gaseous fluid consisting of a cylinder having intake and outlet ports near its opposite ends, and a cylinder head and containing a rotary member near one end and a chambered reciprocal compressive member near its opposite end, a port in the chambered rotary member adapted to, at times, register with the intake port, valve controlled ports in one end of the chambered rotary member, the adjacent end of the compressive member having valve controlled ports, means whereby the rotation of the rotary member imparts axial reciprocal movement to the compressive member and means for preventing rotation of the reciprocal compressive member consisting of a guideway formed in the interior side of the compressive member and

a fixed guide upon the cylinder head and engaging the said guideway.

6. A compressor for air and other gaseous fluids consisting of a cylinder having intake and outlet ports near its opposite ends and a cylinder head at one end and stuffing box at its opposite end; a rotary member registered with and in valvular control of the intake port and in rotative connection with a driving shaft projecting through the stuffing box; the said rotary member being chambered and having a port adapted to, at times, register with the intake port of the cylinder and communicating with the chambered interior, its opposite end being of reduced diameter and surrounded by and protruding through an annular cam, said protruding end having one-way valve ports communicating with and permitting outflow from the chambered interior; a chambered piston between the rotary member and exhaust outlet port and having a projecting annular cam registering with the annular cam of the rotary member and the end of the piston towards the rotary member having one-way valve ports permitting flow into the piston; and means whereby the piston is prevented from rotation.

7. A compressor for air and other gaseous fluids consisting of a cylinder having intake and outlet ports near its opposite ends and a cylinder head at one end and stuffing box at its opposite end; a rotary member registered with and in valvular control of the intake port and in rotative connection with a driving shaft projecting through the stuffing box; the said rotary member being chambered and having a port adapted to, at times, register with the intake port of the cylinder and communicating with the chambered interior, its opposite end being of reduced diameter and surrounded by and protruding through an annular cam, said protruding end having one-way valve ports communicating with and permitting outflow from the chambered interior; a chambered piston between the rotary member and exhaust outlet port and having a projecting annular cam registering with the annular cam of the rotary member and the end of the piston towards the rotary member having one-way valve ports permitting flow into the piston; and means whereby the piston is prevented from rotation and consisting of a guide-way in the interior of its circumferential wall, and a guiding tongue carried rigidly by the cylinder head and disposed to engage the said guide-way and means for returning the piston towards the rotary member.

8. A compressor for air and other gaseous fluids consisting of a cylinder having intake and outlet ports near its opposite ends and a cylinder head at one end and stuffing box at its opposite end; a rotary member registered with and in valvular control of the intake port and in rotative connection with a driving shaft projecting through the stuffing box; the said rotary member being chambered and having a port adapted to, at times, register with the intake port of the cylinder and communicating with the chambered interior, its opposite end being of reduced diameter and surrounded by and protruding through an annular cam, said protruding end having one-way valve ports communicating with and permitting outflow from the chambered interior; a chambered piston between the rotary member and exhaust outlet port and having a projecting annular cam registering with the annular cam of the rotary member and the end of the piston towards the rotary member having one-way valve ports permitting flow into the piston; and means whereby the piston is prevented from rotation and consisting of a guide-way in the interior of its circumferential wall, and a guiding tongue carried rigidly by the cylinder head and disposed to engage the said guide-way and means for returning the piston towards the rotary member.

with a driving shaft projecting through the stuffing box; the said rotary member being chambered and having a port adapted to, at times, register with the intake port of the cylinder and communicating with the chambered interior, its opposite end being of reduced diameter and surrounded by and protruding through an annular cam, said protruding end having one-way valve ports communicating with and permitting outflow from the chambered interior; a chambered piston between the rotary member and exhaust outlet port and having a projecting annular cam registering with the annular cam of the rotary member and the end of the piston towards the rotary member having one-way valve ports permitting flow into the piston; and means whereby the piston is prevented from rotation and consisting of a guide-way in the interior of its circumferential wall, and a guiding tongue carried rigidly by the cylinder head and disposed to engage the said guide-way and means for returning the piston towards the rotary member.

9. A compressor for air and other gaseous fluids consisting of a cylinder having intake and outlet ports near its opposite ends and a cylinder head at one end and stuffing box at its opposite end; a rotary member registering with and in valvular control of the intake port and in rotative connection with a driving shaft projecting through the stuffing box; the said rotary member being chambered and having a port adapted to, at times, register with the intake port of the cylinder and communicating with the chambered interior, its opposite end being of reduced diameter and surrounded by and protruding through an annular cam, said protruding end having one-way valve ports communicating with and permitting outflow from the chambered interior; a chambered piston between the rotary member and exhaust outlet port and having a projecting annular cam registering with the annular cam of the rotary member and the end of the piston towards the rotary member having one-way valve ports permitting flow into the piston; and means whereby the piston is prevented from rotation and consisting of a guide-way in the interior of its circumferential wall, and a guiding tongue carried rigidly by the cylinder head and disposed to engage the said guide-way and means for returning the piston towards the rotary member.

In testimony whereof I have signed my name to this specification in the presence of two witnesses.

CARL W. VOLLMANN.
